E. W. H. Bass
Mustache Guard
St. B. Kidder

United States Patent Office.

E. W. H. BASS, OF QUINCY, MASSACHUSETTS.

Letters Patent No. 100,586, dated March 8, 1870.

IMPROVEMENT IN MUSTACHE-GUARD FOR DRINKING-VESSELS.

The Schedule referred to in these Letters Patent and making part of the same

To all whom it may concern:

Be it known that I, E. W. H. BASS, of Quincy, in the county of Norfolk, and State of Massachusetts, have invented an Improved Mustache-Guard; and I do hereby declare that the following, taken in connection with the drawings, which accompany and form part of this specification, is a description of my invention sufficient to enable those skilled in the art to practice it.

This device, which I term a mustache-guard, is designed, as its name denotes, for a guard to prevent contact of a person's mustache with fluid when drank from a tumbler or other hollow receptacle, and is so made that it may be readily applied and adjusted temporarily to any vessel from which fluid is to be drank, within usual reasonable limits of size and form.

It consists of bars of metal or other suitable material, jointed together, and with their ends separated into parts turned downward, so that one part of each end will go over the rim, and so that the other part will go into the vessel within the rim, both parts bearing against the rim, the bars being turned on the joint so as to leave an opening between them and the rim, through which fluid can flow from the vessel to the user's lips while his mustache rests on the bars, which extend over the vessel like a bridge.

In the drawings—

Figure 1 shows, in elevation, one of my guards attached to a tumbler.

Figure 2 is a plan of what is shown in fig. 1.

Figure 3 is a reversed plan of the guard removed from the tumbler, and extended to its greatest length.

Figure 4 is a plan of the same guard, folded into its smallest compass.

Figures 5 and 6 show modified forms of the guard.

Fig. 6 shows the simplest form of guard, made of

two bars *a* *b*, pivoted together at *c*, the outer ends of each bar being bifurcated, and the parts *d* and *e* bent downward, the parts *e* extending further from the center *c* than the parts *d*, so that the former will go upon or over the outside of the vessel *f*, while the latter goes inside of the rim of *f*.

In figs. 1, 2, 3, and 4, one of the bars *a* has a jointed end piece, *g*, attached to it, by which the guard can be more readily attached to the vessel *f*, as the guard can be more readily and extensively flexed than it can with a single joint, and by which it can be shut up into smaller compass, to be carried in the pocket, than would be the case if made with two bars *a* and *b*, singly.

In fig. 5, each bar *a* and *b* is shown as provided with an end piece, *g*, increasing the capacity of flexure in the guard.

The parts *d* and *e*, when made of thin and comparatively soft sheet metal, can be readily bent to shut over rims of vessels of different thicknesses, though when set so as to be fit for vessels of moderate thickness, the guard holds with sufficient firmness on thinner vessels by the contact produced by flexure of the device.

The guard is placed with the parts *d* and *e* over the rim of a vessel, and is made to gripe the rim by flexing the arms *a* and *b*, or the pieces *g*, or both, to suit the requirements of the case.

I claim a mustache-guard made of two jointed arms, with or without jointed end pieces, when provided with parts *e* and *d*, substantially as and for the purpose described.

E. W. H. BASS.
